HEADBOARD

John J. McLaughlin, 2700 Absecon Blvd.,
Atlantic City, N.J. 08401

Filed Feb. 16, 1973, Ser. No. 333,178

Term of patent 14 years

Int. Cl. D6—01

U.S. Cl. D6—80

FIG. 1

FIG. 2

FIG. 3

FIG. 4

FIG. 5

FIG. 6

FIG. 1 is a front elevational view of a headboard showing my new design;

FIG. 2 is a rear elevational view;

FIG. 3 is a right side elevational view;

FIG. 4 is a left side elevational view;

FIG. 5 is a top plan view; and

FIG. 6 is a bottom plan view.

I claim:

The ornamental design for a headboard, substantially as shown.
